to Underwood Elliott Fisher Company, New
York, N. Y., a corporation of Delaware

Application May 27, 1932, Serial No. 613,868

11 Claims. (Cl. 45—68.2)

This invention relates to carrying cases for portable typewriters. Such a case usually includes a portion forming a base to which the typewriter is attached and a deep cover-portion, the two portions being detachably hinged together.

To permit the use of the typewriter-carrying case for other purposes, as, for example, to serve as an overnight bag, it is provided that the typewriter may be easily and quickly removed from the base-portion. The typewriter is secured to the base-portion so as not to interfere with such other use of the case, nor to be subject to loss or injury when the typewriter is removed. The typewriter must also be easily and quickly replaceable upon the base-portion and when so replaced must be retained securely.

The present improvements provide an elongate clamp or bolt slidably mounted on the base-portion, the bolt being formed with a pair of spaced jaws that, when the bolt has been moved home, overlap circumferential flanges or shoulders of a pair of the cushioning feet usually fastened to the bottom of the typewriter. The jaws are formed so as to overlap the foot-flanges half-way around. Means forming a pair of spaced stationary jaws, of suitable form, may complete, circumferentially, the overlapping of the foot-flanges, said spaced stationary jaws being secured to the base-portion opposite the jaws of the slidable bolt.

The bolt engages preferably the front pair of typewriter-feet, and co-operating therewith, to form three-point attaching means, there may be an anchor-piece located centrally at the rear bottom margin of the typewriter-frame, and engaged by suitable means attached to the base-portion.

In one form of the invention illustrated herein, the stationary jaws are provided, and these, with the bolt-jaws, when the bolt is home, form rings encircling and overtopping the foot-flanges, and thereby, in co-operation with the secured rear anchor-piece of the typewriter-frame, retain the typewriter on the base-portion.

In another form of the invention illustrated herein, the stationary jaws are omitted, the jaws on the bolt, half encompassing and overtopping the foot-flanges, being sufficient to hold the typewriter down upon the base-portion. In this arrangement, in order to secure the typewriter against sidewise displacement, sockets fitting the feet of the typewriter are sunk into the base-portion just deep enough so that the edges of the sockets may prevent said sidewise displacement,

When the typewriter is in use, the cover-portion is generally completely removed. Heretofore the hinging means were usually arranged so that by lifting the cover to open the case, the cover also became fully detached from the base-portion in order that it might be laid aside. In using the case for other purposes, such detachment or separation of the cover and base portions, automatically resulting when the case is opened, is inconvenient when it is desired to open the case for access to its contents or for putting things into it.

The present improvements, therefore, provide hinging means arranged to keep the base and cover portions together when the case is merely opened, and, furthermore, arranged so that, when required, the cover may be completely detached from the base.

In a certain style of carrying case, the base-portion is a rectangular flat board, over the side edges of which the sides of the cover-portion are telescopically fitted. For hinging the two together, the present improvements provide novel hinging devices. At one point of the case, preferably at one of the rear bottom corners, there are a pintle and a socket which may be made separable by mounting one or the other (preferably the pintle) on a lever pivoted to the top of the baseboard. A spring acts on the lever so that normally the pintle is yieldably held within the socket. At the opposite rear bottom corner of the case, another pintle and a socket are provided, and these may be fixed, that is to say, neither one is movable with respect to the base or cover portion to which it is attached.

By swinging the pintle-lever, its pintle is withdrawn from the socket, and that corner of the cover-portion may be slightly raised, whereupon the base and cover portions may be separated at the opposite corners to disengage the fixed pintle and socket. The pintle-carrying lever may have an arm extending along the edge of the baseboard in such manner that when the cover-portion is in place, the side of the cover serves as a stop to prevent rotation of the pintle-lever, and thus locks the lever-carried pintle within its socket.

In a similar manner, the cover, when in place over the base-portion, may also serve as a lock for the slidable clamp or bolt which simultaneously engages both front feet of the typewriter, said clamp or bolt being provided with an extension which just abuts the inner side of the cover when the bolt is moved home. Unless the bolt is moved home, said extension will overlap the side edge of the base-portion and prevent the closing

of the cover-portion thereover. It is thus assured that when the cover is closed over the base-portion, the typewriter within cannot become loosened from the base-portion.

5 In a certain other style of case, the sides of the base-portion are upturned to form a shallow rim. For this style of case, the present improvements provide a hinge formed of two leaves, one leaf carrying a pintle, and the other leaf being curled 10 to form a knuckle for said pintle. The pintle-carrying leaf is also formed with a rest upon which the pintle-receiving knuckle of the other leaf may rest while said knuckle is being slid over the pintle. The pintle-receiving knuckle may 15 have a transverse hole in which may be retained a spring-pressed detent-plunger co-operating with a groove in the pintle for yieldably holding the cover and base portion in hinged relation, it being understood that, axially of the pair of 20 spaced pintles, the cover and base portion may be shifted relatively to one another to either separate them or bring them together again.

It will also be understood that preparatory to so bringing them together again, the pintle-receiving knuckles of the hinges may rest upon and be guided by the aforesaid rests formed on the 25 pintle.

For use with the style of the case in which the edges of the base are upturned, the present 30 improvements afford means for locking the bolt in position to hold down the typewriter-feet, said locking means being constructed to also serve for conveniently shifting the clamp-bolt.

Means are also provided for retaining a supply 35 of stationery within the case.

The clamping means and hinging devices are so arranged as not to impair the use of the case for general purposes, the clamping means being arranged close to the top of the base so as to take up a minimum of room and also so that there 40 are no loose parts subject to loss or injury when the typewriter is removed. The same is also true of the pintle-lever.

Other features and advantages will hereinafter 45 appear.

In the accompanying drawings,

Figure 1 is a sectional side view of a carrying case, showing the typewriter in place.

Figure 2 is a perspective view, showing the 50 cover and base portions of the case opened up and separated, and also showing one form of clamping means.

Figure 3 is a top plan view, showing details of the hinging means shown in Figure 2.

Figure 4 is an enlarged view of one end of the 55 clamping bolt overtopping a flanged or shoulered typewriter-foot, and also showing details of said foot.

Figure 5 is a top plan view, illustrating how 60 the cover-portion of the case, when closed over the base-portion, serves to lock the pintle-lever and also to lock the clamp-bolt in the position in which it holds down the typewriter-feet.

Figure 6 shows details of one form of hinge- 65 device.

Figure 7 is a top plan view, illustrating the arrangement of the clamping means embodying the stationary lips, said view also showing means for locking the clamping bolt in its home position.

Figure 8 is a perspective view of one end of the 70 clamping bolt and associated lip, and shows details of bolt locking and operating means.

Figure 9 is a perspective view of one form of 75 case having a base-portion with upturned edges,

and showing said case open to illustrate the arrangement of leaf-hinges, and the arrangement of clamping means and the means for locking the clamping means.

Figure 10 is a detail view of one of the leaf- 5 hinges.

Figures 1, 2, 3 and 5 represent a carrying case in which a rectangular flat board forms a base 15, on which is to be detachably supported a typewriter 16. A deep cover 17 has its sides telescopically fitting over the side edges of said base 15. Fastened to the inner vertical corners of said cover 17 are quartered pieces 18, against the outer ends of which the inner surface of the base 15 abuts, to position said base flush with the outer 15 rim of the cover.

Fastened to the bottom of the typewriter 16 are the usual four cushioning feet, one pair of feet 19 being toward the rear, and the other feet 20 being toward the front of the typewriter. The top of 20 the base 15 has depressions 21 (Figure 2), into which the feet 19, 20 are seated for locating the typewriter and retaining it against shifting around on said base. From the rear bottom margin of the typewriter, and centrally thereof, there 25 projects a hook or tongue 22, which, as set forth in my pending application, 570,300, filed October 22, 1931 (now Patent No. 1,880,891, dated October 4, 1932), serves to hold the rear end of the typewriter against the baseboard 15, the latter being 30 provided with a strap 23 forming an eye in which the tongue 22 is entered as the typewriter is set upon the base 15.

For holding down the front of the typewriter, the present improvements provide an elongate 35 clamp-bolt 25 for engaging shoulders 26 of the front feet 20. The bolt 25 is slidably guided and retained on the base 15 by means of headed screws 27, having shanks driven into the base 15 and slidably fitting elongate holes 28 of the bolt 25. 40 A strap 29 may overlie one end of the bolt 25, and is fastened to the base 15, said strap co-operating with the head of one of said screws 27 in holding said end of the bolt against the baseboard.

The bolt 25 may be formed so that the greater 45 portion thereof lengthwise lies upon the base 15. The bolt may be formed of sheet-metal, and, for overtopping the shoulders 26 of the front feet 20, it may have struck up therefrom portions forming jaws 30 spaced from the base 15 sufficiently so that said jaws may overtop said shoulders 26. Semi-circular openings or notches 31 of the jaws are constricted continuations of perforations 32 formed in the bolt-portions lying next to the base 15, said perforations being large 50 enough to admit the bottoms of the front feet 20 in position to be engaged by the jaws 30 when the bolt is slid home.

From Figure 5, it will be seen that the bolt 25 spans both front feet 20 of the typewriter, and it 60 will be seen that a single shift of the bolt either brings it into position to lock both feet to the baseboard, as indicated in Figure 5, or into position to clear both feet, so that the typewriter may be withdrawn from the base, as is evident from 65 Figure 2.

That end of the bolt which moves inwardly when the bolt is shifted home is arranged to be flush or slightly within the side edge of the base 15 when the bolt has been so shifted. Thus, 70 when the cover 17 is closed over the base 15, the side 33 of the cover serves to lock the bolt in its home position, as seen in Figure 5. Said end of the bolt which thus is obstructed by the side 33 of the cover may also have a turned-up finger- 75

piece 24, whereby the bolt may be manipulated for shifting it to either one of its positions. Inasmuch as the cover 17 when closed down upon the base 15 prevents the bolt 25 from being shifted 5 out of locking engagement with the front typewriter-feet 20, the possibility of the typewriter becoming loosened from the base 15 while said typewriter is being carried around within the case is precluded. It is also assured that the 10 typewriter is properly clamped down upon the base 15 when the cover 17 is closed over said base, because, if the typewriter is not so clamped down, it will be because the bolt 25 has not been shifted home, and hence the end of the bolt carrying 15 the finger-piece 24 will project beyond the side of the base and will bar closing of the cover thereover. Secured to the tops of the shoulders 26 of the typewriter-feet 20, there may be metal washers 35 to guard said shoulders against wear 20 by the clamp-bolt 25. The front feet 20 depend from lugs 12 of the typewriter-framework and may be secured by suitable means as, for example, a headed screw 13 passing through the lug 12 and foot 20 and threaded into a nut (not shown) molded or sunk into the bottom of the foot. A washer 14 may underlie the head of the screw 13, the top of the foot having a reduced portion 11 entered into the lug 12. The feet 19 are similarly fastened.

30 For detachably hinging the cover 17 to the base 15 in such a way that the case may be opened without the cover and base becoming immediately separated, the following hinge-devices are provided. Into the sides of the bottom rear corners 35 of the cover, there are fastened plates 36, having elongate holes 37 forming sockets for receiving hinge pintles. The elongation of said holes 37 permits the base 15 to move forward slightly as the case is opened. By this slight forward movement 40 the rear edge of the base 15 clears the cover 17. One of said pintles, namely, the pindle 38, is rigidly fastened to one of the rear corners of the base 15, said pindle 38 projecting laterally from an angle-piece 39 which may be fitted into 45 said corner of the base, as indicated in Figures 2 and 3, and may be secured by rivets 40. A pindle 41 at the opposite rear corner of the base 15 is mounted so that it may be withdrawn from its socket 37 in order that the cover 17 and the base 50 15 may be separated. For so mounting said pindle 41, there is a lever 42, having arms 43 and 44 extending from opposite sides of a flanged collar 46 (Figure 1), whose flange 45 is sunk into the base 15, so that the fulcrum forming collar 46, 55 topping said flange, projects above said base to receive the lever 42. A headed screw 47 passes through said collar and is threaded into a nut 48, which may be driven into the under side of the base 15, said screw 47 and nut 48 serving to 60 clamp the collar 46 down upon the base 15, and the screw-head serving to hold the lever 42 in place. The rearwardly-extending arm 43 has a downwardly-bent portion 49 from which the pindle 41 may project. For clearing said downwardly-bent portion 49 of the arm 43, the corner 65 of the base may have a jog 50, Figure 3. Said portion 49 of the lever 42 does not extend to the bottom of the base, and a plate 51 may therefore be sunk into said bottom of the base to form 70 a closure for said jog 50. For yieldably holding the lever 42 in the position in which the pindle 41 is within its socket 37, there presses upon the arm 43 of said lever a spring 52. To afford room for said spring 52, the side of the jog 50 may have 75 a hole 53 forming a socket, against the bottom of

which one end of said spring may react. The other end of the spring reacts against a head 54, which may be part of the pindle 41. A pin 55, driven into the base 15, serves as a stop to limit the rotation of the pindle-lever 42, that is to say, 5 with the arm 44 of said lever abutting said stop, a finger-piece 56, formed on the end of said arm, will be just within the side edge of the base 15, and the pindle 41 will be in the position in which it is when received within the socket 37. It will 10 be evident that with the cover 17 closed down upon the base 15, the pindle 41 cannot withdraw from its socket 37, because the side 33 of said cover prevents rotation of the lever 42. Figure 3 indicates how the cover 17 and base 15 may be 15 separated or brought together again when the lever 42 is swung to retract the pindle 41 within the jog 50 of the base.

The present improvements provide simple means for storing within the case a supply of 20 stationery. Fastened centrally to the rear side 58 of the cover, and spaced from the top 59, is an angle-piece forming a ledge 60, which with said top 59 of the cover forms a rack, into which may be received and held one side-end of a 25 stack of stationery. A swingable bail 63 is pivoted between brackets 64, fastened to the front side 65 of the cover. The pintles of the bail which are received by the bracket 64 have turned ends 66, against which may react one end of springs 30 67 which may be curled around said pintles, the other ends of said springs each reacting against the portion of the bracket 64 that is fastened to the front cover-side 65. The springs 67 cause the bail 63 to press toward the top of 35 the cover 59, and hence the stack of stationery is held against said cover by said bail and may be withdrawn when the bail 63 is swung away. The inner side of the cover-top 59 may have the 40 usual plate 69, against which the swiveled line-space handle 70 abuts when the cover is closed over the typewriter. At the front side of the cover, there are provided the usual carrying handle 71 and a portion 72 of the usual lock, said lock having a complementary portion 73 at the 45 front edge of the base 15. It will be seen that the clamping and hinging organization is such as not to interfere with the use of the case for other purposes than that of carrying a typewriter. The clamp-bolt 25 is substantially flat 50 and offers no obstruction. It constitutes a single piece serving to hold down both front feet of the typewriter and is easily manipulated, to the end that the typewriter may be quickly withdrawn from the base or may be quickly and securely 55 replaced upon the base. When using the carrying case as an overnight bag, for example, the base 15 becomes a top lid, which may be opened and closed without detachment from the cover-portion 17. For facilitating manipulation of the 60 lid to open it from the bottom-portion 17, it may be provided with a lip 74, which may be made accessible by relieving the edge of the front side 65 of the cover, as at 75.

Figures 7, 8 and 9 illustrate another organization for clamping and locating the typewriter 16 to a base 76. In this organization, there is also used an elongate duplex clamp-bolt 77 for simultaneously engaging both front feet 20 of the typewriter. The foot-receiving depressions in the 70 base shown in Figure 2, and which serve to locate and hold the typewriter against moving around on the base, are omitted, the base 76 to which said other organization is applied not having said depressions. In lieu thereof, there are pro- 75

vided fixed jaws 78, 79, each having a notch 80 formed to half encompass the neck which tops the shoulder 26 of the typewriter-foot 20. The encompassing of said neck is completed by a notch 81 in a jaw 82 of the clamp-bolt 77, said clamp-bolt having two of said jaws 82, one for each foot 20 of the typewriter. The fixed jaws 78, 79 together with the jaws 82 of the movable bolt 77, when encompassing the necks of the typewriter-feet 20, serve to locate the typewriter and confine it against moving around on the base when said bolt is shifted home.

The fixed jaws 78, 79 are formed of straps 83 fastened to the base 76 and having upward offsets 84 to bridge said jaws 78, 79 over the bolt-portions 85, said bolt-portions 85 having perforations 86 of suitable form, as indicated, to admit the typewriter-feet 20 when the bolt is open. The offsets 84 of the straps 83 fit the sides of said bolt-portions 85 and thus serve to slidably guide the bolt 77 on the base 76. Said bolt 77 is made of sheet-metal and the portions forming the jaws 82 thereof are struck from the central portion of the bolt which lies against the base, so as to overtop the shoulders 26 of the typewriter-feet 20. Referring to Figures 7 and 9, the portion 85 may, as will be seen at the left end-portion of the bolt, be offset downwardly, as at 87, to pass under and abut the fixed jaw 78, it being noted that the portions of the fixed jaws 78, 79 and of the movable jaws 82 which embrace the feet 20 are preferably on the same level. The offset at 87 may not bring the bolt-portion 85 to lie against the base and there may be formed near the end 88 of said bolt another offset which brings said end down to lie upon the base. An alternative way of bringing the fixed and movable jaws to the same level is seen at the right end-portion of the bolt in which the portion 85 and the jaw 82 are not offset from one another. Instead of such offset, the portion of the fixed jaw 79 around the notch 80 of said jaw is depressed to the level of the movable jaw 82, the diameter at the under side of the depressed jaw-portion being within the sides of the perforations 86.

In carrying out a certain design for the case, the base 76 may be formed with upturned edges 90. Therefore the extent of the outwardly-moved end of the clamp-bolt must be limited, so that when said bolt is shifted, said end does not interfere with said upturned edges 90 of the base. For shifting or locking the bolt under these conditions, there is provided a plate 91 slidably retained in a guide 92 fastened to the base 76. For slidably guiding the plate 91, said guide 92 has at one end an upturned edge 93 and a similar opposite edge that is turned over the plate as seen at the portion 94 of said guide. The other end of the guide 92 has a similar turned-up and over portion 95, said portion 95 co-operating with the side of the strap 83 to guide the plate 91 laterally. It will be noted that in order to so guide the plate 91, the strap 83 at the right is widened to the extent of portions 83^a of said strap. The movement of the plate 91 transversely of the bolt 77 is translated into bolt-shifting movement by means of an inclined cam-slot 96 in said plate, said cam-slot engaging a pin 97 projecting downwardly from the end of the clamp-bolt. The plate 91, held down along one side thereof by the turned-over portions 94, 95 of the guide, is also held down on its opposite side by the end of the bolt, said end of the bolt being therefore offset downwardly, being bent 75 at 98 to abut the top of the plate 91. For manipu-

lating the plate 91 to shift the bolt, it may have an upturned finger-piece 99.

The inclined cam-slot 96 has a portion 100 which is perpendicular to the clamp-bolt. Thus, when the plate 91 has been moved forwardly to move the clamp-bolt home, said portion 100 engages the bolt-pin 97 and, being square with the direction of bolt-movement, locks the bolt in its home position. The plate 91 may, itself, be locked when it has been moved to shift the bolt home, the locking of the plate being effected by means of a latch-lever 102 pivoted to the plate on a headed stud 103. Said latch-lever 102 has an arm 104 notched at its end to engage a corner of the turned-over portion 94 of the guide 92, the lever being arranged on the plate, as seen in Figure 8. An upturned finger-piece 105 of the latch-lever is disposed alongside of the finger-piece 99 of the plate 91, so that preparatory to releasing and shifting said plate, both the finger-pieces 99 and 105 may be grasped simultaneously. The closed end of the cam-slot portion 100 may be positioned to limit the forward movement of the plate 91, by abutment with the pin 97, so that the tips of the latch-arm cannot get wholly behind the corner of the guide-portion 94 which said arm engages. It will be understood that the plate 91 may be drawn forwardly far enough so that the end of the latch-arm 104, when the arm is being withdrawn, may be swung clear of said corner preparatory to shifting the plate rearward. A spring 107 coiled around a stud 108 presses upon the latch-arm 104, so that said arm may automatically snap into locking relation with the corner 35 of the guide-portion 94 when the plate 91 has been moved forwardly. Figure 7 shows the plate 91 moved rearwardly in consequence of which the bolt 77 has been moved to the right to separate the clamping jaws for removal of the typewriter or for replacement thereof upon the base 76.

With the organization seen in Figures 7 and 9, there are also used an anchor-hook 22 at the rear of the typewriter and an eye-piece 23 fastened to the base 76. With the jaws of the clamps open, and the typewriter 16 turned by swinging it about the eye-piece 23, as indicated by the skewed broken outline representing said typewriter 16, Figure 7, the front feet 20 may either be admitted to the perforations 86 of the clamp-bolt 77 or they may be withdrawn from said perforations. It will be evident that when the typewriter is shifted from said skewed position to its normal position shown by another broken outline, the necks of the front feet 20 will then be brought within the notches 80 of the fixed jaws 78, 79. When the typewriter is in its normal position, the bolt is moved to the left by shifting the plate 91 forwardly whereupon the bolt will also be locked by said plate as already explained, the parts being then in the position seen in Figure 9, to securely hold the typewriter to the base 76.

Hinges arranged for application to the carrying case having a base with upturned edges are seen in Figures 6, 7, 9 and 10. Each hinge includes a pair of leaves 110, 111. The leaves 110 are fastened to the rear side of the upturned edge 90 of the base 76, each leaf 110 having at one end a socket 113 in which is fastened a pintle 114. Said pintle projects far enough from said socket to enter the full length of a knuckle 115 formed on each of the pair of leaves 111 which are fastened to the rear wall of the top cover 75

61. Each pintle carrying leaf 110 includes a rest 118 disposed beyond the end of the pintle. The hinge-knuckles 115 forming part of the cover 117 are laid against the rests 118, to guide them over the pintles 114, thus conducing to the celerity with which the cover and base may be brought together in hinged relation. Each rest 118 may have a groove 119 into which the knuckle 115 may be set to facilitate the guiding of the 5 knuckle onto the pintle. A detent-device may be applied to one of the hinges to prevent unintended relative lateral displacement of the cover and base after they have been brought together. Said device is preferably yieldable so 10 that, while ordinarily preventing such displacement, the cover may, when desired, be separated from the base by overcoming said detent-device. To this end, the knuckle 115 may have a transverse stem 120 which may be drilled to receive 15 a detent plunger or ball 121, a spring 122 pressing upon said ball and being backed by a screw 123 threaded into the end of the stem. When the cover and base are assembled in hinged relation, the spring 122 presses the ball 121 into 20 the groove 124 on the pintle and thus the cover and base are yieldably held together.

The hinged leaves 110, 111 may be sunk, as indicated at 125, Figure 6, into case-portions to which they are fastened by rivets 126. The bottom edge of the cover 117 may have a projection 127 which, fitting within the upturned edges 90 of the base, prevents relative lateral displacement of the cover and the base when said cover is closed upon the base.

35. Variations may be resorted to within the scope of the invention, and portions of the improvements may be used without others.

Having thus described my invention, I claim:

1. The combination of clamping means for 40 securing a typewriter to a baseboard, said typewriter having a rear device detachably interlocking with a co-operating device on said baseboard, and also having a pair of shouldered front feet resting on said baseboard, said clamping 45 means including an elongate clamping bolt slidably mounted on the baseboard and spanning said feet, said bolt having a pair of spaced jaws formed to overtop and half encompass the shoulders of said feet when the bolt is shifted home 50 in a longitudinal direction and to be free of said feet when the bolt is shifted in the opposite direction, said baseboard having means for locating said feet thereon preparatory to shifting the clamping bolt home, and a cover securable upon 55 said baseboard, said bolt being locked in home position by said cover.

2. The combination of clamping means for 60 securing a typewriter to a baseboard, said typewriter having a rear attaching means detachably connected with a co-operating means on said baseboard, and also having a pair of sound insulating shouldered front feet resting on said baseboard, said clamping means including an elongate clamping bolt slidably mounted on the 65 baseboard and spanning said feet, said bolt having a pair of spaced apertures to admit said feet, portions of the bolt, including parts of said apertures, being offset for overlying and partly encompassing shoulders of said feet whereby 70 said typewriter is sound insulated from both said bolt and baseboard, said baseboard having means for locating said feet thereon preparatory to shifting the clamping bolt home, and means movable relatively to said clamping bolt to lock the 75 same in home position.

3. A baseboard, for supporting a typewriter provided with a pair of shouldered front feet and also provided with means spaced from said feet for interlocking with complementary means mounted on said baseboard, an elongate clamping bolt slidably mounted on said baseboard and arranged to overtop the shoulders of said feet when the bolt is shifted home in a longitudinal direction and to be free of said feet when the bolt is shifted in the opposite direction, and a removable cover for said baseboard, said clamping bolt being arranged so as to be locked in its home position by said cover when the latter is in place.

4. A carrying case arranged for transporting a portable typewriter and also arranged to serve for other purposes, as for example, an overnight bag, said case including, in combination, a base-portion, a deep body-portion, the typewriter having a rear anchor-piece, and also having feet 20 including a pair of shouldered front feet, a member forming part of said base for interlocking with said anchor-piece, clamping means for engaging said front feet, said clamping means including an elongate clamp-bolt slidably mounted on said base, said clamp-bolt having jaws 25 formed to half encompass the shoulders of said feet and being further formed so that when said bolt is shifted to one position, said jaws overtop said shoulders, and, when shifted to the other position, said jaws are free of said feet to permit removal of the typewriter from said base, said member and said clamp-bolt being substantially flat, so as to occupy a minimum of room above said base, and hinging devices for 30 detachably hinging said body-portion and base together, said hinging devices including a pair of pintles on the base, a pair of sockets on the body-portion for receiving said pintles, and means mounting one of said pintles so that it 35 may be retracted preparatory to separating or bringing together the body-portion and base, means being provided to jointly lock the pintle-mounting means and clamp-bolt in their effective positions.

5. A carrying case arranged for transporting a portable typewriter and also arranged to serve for other purposes, as, for example, an overnight bag, said case including, in combination, a base-portion, a deep body-portion, the typewriter having a rear anchor-piece, and also having feet including a pair of shouldered front feet, a member forming part of said base for interlocking with said anchor-piece, clamping means for engaging said front feet, said clamping means including an elongate clamp-bolt slidably mounted on said base, said clamp-bolt having jaws formed to half encompass the shoulders of said feet and being further formed so that when said bolt is shifted to one position, said jaws overtop said shoulders, and, when shifted to the other position, said jaws are free of said feet to permit removal of the typewriter from said base, said member and said clamp-bolt being substantially flat, so as to occupy a minimum of room above said base, and hinging devices for detachably hinging said body-portion and base together, said hinging devices including a pair of pintles on the base, a pair of sockets on the body-portion for receiving said pintles, and means mounting one of said pintles so that it may be retracted preparatory to separating or bringing together the body-portion and base, said clamp-bolt, and pintle-mounting means being arranged so as to 75

be locked by the body-portion when the latter is closed over the base.

6. The combination with a baseboard, for supporting a typewriter having a pair of feet resting on said baseboard, of a clamp-bolt slidably mounted on said baseboard, so as to be shiftable between two positions, one position for engaging said feet and the other position for being free of said feet, and a slide mounted on said baseboard for movement transversely of said clamp-bolt, said clamp-bolt and slide having co-operating camming devices whereby movement of said slide in one direction shifts said clamp-bolt to one position to engage said feet, and whereby movement of said slide in the opposite direction shifts said clamp-bolt to the other position to free said feet.

7. The combination with a baseboard, for supporting a typewriter having a pair of feet resting on said baseboard, of a clamp-bolt slidably mounted on said baseboard, so as to be shiftable between two positions, one position for engaging said feet and the other position for being free of said feet, and a slide mounted on said baseboard for movement transversely of said clamp-bolt, said clamp-bolt and slide having co-operating camming devices whereby movement of said slide in one direction shifts said clamp-bolt to one position to engage said feet, and whereby movement of said slide in the opposite direction shifts said clamp-bolt to the other position to free said feet, said camming devices being arranged to lock the clamp-bolt in its feet-engaging position against movement independently of said slide.

8. The combination with a baseboard, for supporting a typewriter having a pair of feet resting on said baseboard, of a clamp-bolt slidably mounted on said baseboard, so as to be shiftable between two positions, one position for engaging said feet and the other position for being free of said feet, a slide mounted on said baseboard for movement transversely of said clamp-bolt, said clamp-bolt and slide having co-operating camming devices whereby movement of said slide in one direction shifts said clamp-bolt to one position to engage said feet, and whereby movement of said slide in the opposite direction shifts said clamp-bolt to the other position to free said feet, and a releasable spring-pressed latch to lock said slide when it has been moved to shift the bolt to its feet-engaging position.

9. For use with a typewriter having a pair of cushion feet having shouldered exteriors, a baseboard, a pair of jaws fixed to said baseboard and arranged thereon to engage said feet at similar sides and formed with portions to half encompass and overtop the shoulders thereof, and a duplex clamp-bolt slidably mounted on said baseboard, said clamp-bolt spanning said feet and having jaw-portions at its ends arranged to overtop said shoulders on the sides of the feet opposite to the sides engaged by said fixed jaws when the bolt is shifted in one direction, and to withdraw from said feet when the bolt is shifted in the opposite direction for opening the jaws and removing the typewriter from the baseboard.

10. A portable typewriter-hold-down device associated with a carrying-case baseboard on which a pair of spaced feet of the typewriter rest, each foot having a base which rests on said baseboard, a hold-down shoulder, and a neck above the shoulder, said hold-down device including a single retractable clamp-element spanning said feet, said clamp-element comprising a bar on the baseboard, said bar having portions above said baseboard to engage said feet, the bar being held down on said baseboard, for shift between clamping and retracted positions, apertures being provided in the bar for admitting said feet to contact with the baseboard when the clamp-element is in retracted position, said apertures being formed so that said portions clutch the necks of the feet, and overlap the foot-shoulders to hold the feet down on the baseboard, when the clamp is shifted to effective position, the baseboard and hold-down device co-operating to lock the typewriter against both lateral and vertical displacement relative to the baseboard during transportation, and a cover by which the clamp-element is locked in effective position.

11. For use with a typewriter having a pair of cushion feet, each formed with a shoulder, a baseboard, a pair of jaws, one for each foot, said jaws fastened to said baseboard to clasp over the shoulders of the feet, each jaw being fixed at the same side of its own foot as the other jaw, so that movement of the typing machine in one direction may release both feet from their fixed jaws, and clamping jaws connected together and mounted upon said baseboard for movement in a single direction, to close as a unit against said fixed jaws.

WILLIAM A. DOBSON.
